DESIGN FOR A COMBINED BEVERAGE DISPENSING AND SERVING TRAY UNIT

Charles P. Kimmel, Gary, Ind.

Application October 2, 1940, Serial No. 95,575

Term of patent 14 years

To all whom it may concern:

Be it known that I, Charles P. Kimmel, a citizen of the United States, residing at Gary, in the county of Lake and State of Indiana, have invented a new, original, and ornamental Design for a Combined Beverage Dispensing and Serving Tray Unit, of which the following is a specification, reference being had to the accompanying drawing, forming a part thereof.

Fig. 1 is a perspective view of a combined beverage dispensing and serving tray unit, showing my new design; and

Fig. 2 is a top plan view thereof, on an enlarged scale.

I claim:

The ornamental design for a combined beverage dispensing and serving tray unit, as shown.

CHARLES P. KIMMEL.
